UNITED STATES PATENT OFFICE.

JOHN F. GAIL, OF EVANSTON, ILLINOIS, ASSIGNOR TO SIMMONS COMPANY, OF KENOSHA, WISCONSIN, A CORPORATION OF DELAWARE.

MATTRESS AND LIKE STRUCTURE.

Application filed June 5, 1924. Serial No. 717,977.

This invention has for its object to improve in certain respects that type of mattresses and cushions in which rows of coil springs are retained within a padded casing or sheath in such manner that the springs may not become distorted and may not contact with each other. The invention consists in the novel features of construction hereinafter described, illustrated in the 10 accompanying drawing and particularly pointed out in the claims at the end of this specification.

Figure 1 is a view in vertical section on line 1—1 of Fig. 2, showing a portion of a 15 mattress or cushion embodying my invention. Figure 2 is a plan view (parts being broken away) of the spring-inclosing casing or sheath, with the padded covering removed therefrom. Figure 3 is an enlarged 20 detail view in vertical section on line 3—3 of Fig. 2.

A designates the spring-inclosing casing that may be formed of ticking or other suitable material and will be inclosed preferably by a covering pad B of familiar construction. The casing A is divided into a plurality of compartments by means of vertically disposed partition strips C, these compartments serving to receive the coil 25 springs D that will be disposed preferably but not necessarily in staggered or alternating arrangement, as indicated in Fig. 2 of the drawing. The free top and bottom edges of the partition strips C are united by rows 30 of stitching e to the top and bottom walls of the casing A, the stitching passing through the angularly bent portions of the partition strips C. If desired, the edges of the partition strips may be reverted, as indicated 35 at the bottom of Fig. 1 of the drawing, these reverted edges of the strips C being united to the casing A by rows of stitching e'.

In order to securely hold the coil springs D in a proper relative position and in such 40 manner as to prevent the springs from contacting with each other, I unite adjacent springs by means of relatively stiff ties or connectors E of textile material. These ties E may consist of pieces or sections of webbing folded upon each other, as indicated in 45 Fig. 3 of the drawing. The folded plies of each tie E of webbing may be stitched together as at e, although this is not necessary. As shown, the ties E are also stitched together, 50 as at e', between the spring coils D, and in

the preferred form of the invention, the ties E extend a considerable distance inwardly towards the axes of the various springs and are securely fastened together by staples F.

When the springs D have been united together by the ties of textile material, they will be compressed (as by the usual compression tongs) and inserted into the compartments formed within the casing A by the partition strips C. The ties of textile material E will serve not only to effectively hold the coil springs D in proper relative position, but will also prevent the coils of the springs from contacting with each other and so avoid the danger of noise incident to such contact, as well as the danger of any interlocking or distorting of the springs.

These ties are also effective to prevent interlocking or lapping of the connected portions of adjacent springs when a load is applied to a certain portion of the mattresses, since the inwardly projecting portion of the relatively stiff tie within the adjacent spring will be held flat against the adjacent inner surface of the cushioning pad, and will thereby be prevented from rotating about the coil portion embraced by it sufficiently to permit the adjacent end coils to assume a lapped position.

Since the specific embodiment herein disclosed is merely illustrative of a single application of my invention, it will be understood that the scope of same should be determined by reference to the appended claims, said claims being construed as broadly as possible, consistent with the state of the art.

Having thus described my invention, what I claim as new and desire to secure by Letters Patent is:—

1. In a mattress or like structure, the combination of a plurality of coil springs disposed in a row, means for holding adjacent springs in proper relative position comprising a pair of relatively stiff fabric members disposed one above and one beneath adjacent portions of the end coils of adjacent springs, said members being secured together between the coils so as to space said coils apart, and said members extending a substantial distance inwardly towards the axes of the respective springs and secured together, whereby said coils are prevented from spreading apart, and said members lying in substantially the plane common to the

- end coils of the various springs, cushioning material overlying the springs and a sheet of fabric interposed therebetween; said cushioning material and sheet of fabric forming an abutment for preventing said relatively stiff fabric members from swinging on the respective end coils an amount sufficient to permit lapping of the connected portions of the adjacent springs.
- 10 2. A connecting member for connecting together end coils of adjacent mattress or like springs and comprising a pair of rebent fabric strips forming two-ply elements, said two-ply elements being disposed face to face and stitched together intermediate their ends, and the opposite end portions of the elements being disposed one above and one beneath adjacent portions of said end coils and extending a considerable distance inwardly towards the axes of the respective springs, and said inwardly extending portions being secured together inside of the respective coils so as to prevent spreading apart thereof.

JOHN F. GAIL.
